UNITED STATES PATENT OFFICE.

CHARLES P. STIRLING, OF SOMERVILLE, NEW JERSEY, ASSIGNOR TO COTT-A-LAP CO., OF SOMERVILLE, NEW JERSEY, A CORPORATION OF NEW JERSEY.

METHOD OF CONTINUOUS PRINTING BY LITHOGRAPHY.

1,398,808.

Specification of Letters Patent. Patented Nov. 29, 1921.

Application filed March 19, 1919. Serial No. 283,468.

To all whom it may concern:

Be it known that I, CHARLES P. STIRLING, a citizen of Austria, and a resident of Somerville, county of Somerset, State of New Jersey, (having declared my intentions of becoming a citizen of the United States,) have invented certain Improvements in Methods of Continuous Printing by Lithography, of which the following is a specification.

The object of my invention is to print by lithography in continuous lengths. Heretofore, it has been the universal practice in printing by lithography to print in sheets only, consequently, the use of the printed sheet was limited and, furthermore, a considerable waste resulted in cutting, due to the fact that the sections had to be cut from comparatively small sheets. The invention is particularly adapted for commercial purposes, such as the manufacture of covers for paper boxes, book bindings, etc. At the present time, these covers are printed from engraved copper cylinders by the old and well known method of intaglio printing. This produces effects far inferior to a lithographic process. The present practice of lithography makes the cost prohibitive in many instances, owing to waste.

By my invention, which I will now proceed to describe, I am enabled to print lithographically in continuous sheets of any length desired so that the lithographic sheet will have the same advantages in commercial manufacture as the sheet printed by the engraved copper cylinder.

In the accompanying drawings, I have illustrated one method of carrying out my process, the parts being shown diagrammatically.

Figure 1 is a sectional view through a machine for graining the surface of a cylinder suitable to receive the design;

Fig. 2 is a view illustrating one form of apparatus for transferring the design onto the cylinder; and

Fig. 3 is a diagrammatic view of a lithographic printing machine for making an impression on a continuous sheet of paper by the use of cylinders.

In carrying out my improved process, I first make a cylinder 1 of zinc, aluminum, or other suitable material. I grain the surface of the cylinder in such a manner that it will receive the design.

Fig. 1 illustrates a machine which I may use for graining the cylinder. This machine consists of a trough-shaped base 2 mounted on suitable supports 3 and at each side of the base is a rail 4 on which are mounted the wheels 5. These wheels are adapted to axles, which carry a hopper 6. The hopper has inclined sides and is open at the bottom and is so shaped as to fit the upper portion of the cylinder, which is located in the trough-shaped base. The hopper is reciprocated by a crank 8 having a link 9 connected to one end of the trough. The crank is mounted on the end of a vertical shaft 10 driven from a horizontal shaft 11. On the spindle of the cylinder 1 is a gear wheel 12, which meshes with the gear wheel 13 on a driving shaft 14 and on this shaft is a sprocket wheel 15 around which passes a chain 16 to a sprocket wheel 17 on the shaft 11 so that, as the cylinder rotates, the trough is reciprocated. A number of small balls 7 of steel, or other suitable material, is placed in the hopper, as shown, and I also place in the hopper finely divided flint with a given quantity of water so that, as the cylinder is rotated, a certain amount of flint passes between the balls and the cylinder, and the balls are agitated by the reciprocating hopper. This action causes the balls to force the flint against the cylinder and thus grain the surface in a manner suitable for lithographic printing.

After the cylinder has been grained, it is removed from the machine illustrated in Fig. 1 and mounted in the machine illustrated in Fig. 2, which is a transfer machine, and consists of a bed 18 on which is mounted a carriage 19 having bearings for a shaft 20 carrying a transfer drum 21 covered with rubber, or other suitable material. It also has bearings for the spindles of the cylinder 1 on which the design is to be transferred. Secured to the bed 18 is a zinc plate 22 on which is the original design. When the roller 21 is rolled over this plate 22, which has been previously inked up, the design is transferred onto the roller and finally transferred from the roller onto the cylinder 1. In the present instance, there is a rack 23 at each side of the bed 18 and a shaft 24 has pinions 25 engaging the rack. On the shaft is a gear wheel 26, which meshes with a pinion 27 on a shaft 28 having a handle 29 by which it is turned. On the transfer

roller 21 is a gear wheel 30 which meshes with one of the racks 23 and on the spindle of the cylinder 1 is a gear wheel 31 which meshes with the gear wheel 30 so that when 5 the carriage is traversed over the plate 22 all of the parts move in register. Care must be taken to have the zinc plate in exact proportion to the grained cylinder in order to produce the desired effect. Any visible defects on the grained cylinder are then 10 retouched and the surface treated in the usual lithographic manner to bring it to the proper condition for printing. The grained printing cylinder, with the design thereon, 15 is taken from the transfer apparatus and located in the printing machine, such as illustrated in Fig. 3. Where two cylinders are used, the cylinder 1 may be duplicated, the number of cylinders depending upon the 20 number of colors in the design.

In Fig. 3, I have illustrated in diagram one form of lithographic press which may be used in carrying out my invention. The two cylinders 1, 1 are mounted in position 25 above an impression cylinder 32. The grained cylinders are geared to the cylinder 32 in the ordinary manner. Above each grained cylinder is an ink fountain 33 and a water fountain 34. 35 is an endless blanket 30 and 36 is an endless delivery belt.

The roll of paper *a* is mounted on a rack 37 and the paper passes around tension rollers 38 and between the impression cylinder and one of the grained cylinders and 35 over the impression cylinder and under the other grained cylinder, then around a guide roll 39 and over the endless belt 36 to the

drying rack 40 where it is formed into loops. This drying rack may be of any construction desired.

From the above description it will be seen that by making the grained cylinder in the manner shown and by transferring the design onto the grained cylinder, the cylinder, or a number of these cylinders, can 45 be mounted on a continuous printing machine so as to produce a continuous sheet having lithographic impressions thereon. This sheet is available for use for many purposes, such as a cover for paper boxes, 50 book bindings, &c. A continuous lithographic sheet can be produced in colors by my improved process more cheaply than by the present method of intaglio printing. Moreover, by printing in continuous sheets, 55 considerable waste is eliminated.

I claim:

The process herein described of preparing cylinders for making continuous impressions and printing therefrom, said process 60 consisting in preparing a cylinder of zinc or similar material, graining the entire surface of the cylinder, then preparing a design on a flat zinc plate, the design being equal to the circumference of the grained 65 cylinder, and finally transferring the design from the flat zinc plate onto a transfer roller and from the roller onto the grained cylinder, preparing the cylinder for printing, and making a continuous impression on paper 70 from the inked grained cylinder.

In witness whereof I affix my signature.

CHARLES P. STIRLING
